(57) **CLAIM**

The ornamental design for a reusable transparent packaging, as shown and described.

DESCRIPTION

FIG. 1 is a front elevational view of one form of the reusable transparent packaging showing the new design;

FIG. 2 is a rear elevational view;

FIG. 3 is a right side view;

FIG. 4 is a left side view;

FIG. 5 is a top plan view;

FIG. 6 is a bottom plan view;

FIG. 7 is a perspective view in a closed position;

FIG. 8 is a perspective view of the packaging with the unfolded flap showing the precut line and reusable fastener with complementary units;

FIG. 9 is a front elevational view of another form of the reusable transparent packaging showing the new design;

FIG. 10 is a rear elevational view;

FIG. 11 is a right side view;

FIG. 12 is a left side view;

FIG. 13 is a top plan view;

FIG. 14 is a bottom plan view;

FIG. 15 is a perspective view in a closed position; and,

FIG. 16 is a perspective view of the packaging with the unfolded flap showing the precut line and reusable fastener with complementary units.
